(57) **CLAIM**

The ornamental design for an electrical connector, as shown and described.

DESCRIPTION

FIG. 1 is a top view of an electrical connector according to my design;

FIG. 2 is a bottom view thereof;

FIG. 3 is a left view thereof;

FIG. 4 is a right view thereof;

FIG. 5 is a front view thereof;

FIG. 6 is a rear view thereof; and,

FIG. 7 is a left, front, top perspective view thereof.

The article is shown with a symbolic break in its length. The appearance of any portion of the article beyond the break lines forms no part of the claimed design. The dashed break lines form no part of the claimed design.
